UNITED STATES PATENT OFFICE

SAUL SCHULHOFF, OF BALTIMORE, MARYLAND

STEEL-WOOL HOLDER

Application filed December 17, 1929. Serial No. 414,800.

The present invention relates to holders and more particularly to holders adapted to securely hold a pad of steel wool or the like.

An object of this invention is to provide a holder for securely engaging a pad of steel wool so as to permit the use of steel wool without engaging the hand or fingers on the wool.

Another object of this invention is to provide a substantially flexible and resilient holder for holding a pad of steel wool.

A further object of this invention is to provide a holder of this character which is flexible and may be secured to a pad of steel wool without the use of tools or the like, and which may be used repeatedly for holding pads of steel wool.

The above and various other objects and advantages of this invention will in part be described in and in part be understood from the following detailed description of the present preferred embodiment, the same being illustrated in the accompanying drawing, wherein:

25 Figure 1 is a bottom plan view of a device constructed according to the present invention;

Figure 2 is a transverse section taken on the lines 2—2 of Figure 1;

30 Figure 3 is a longitudinal section taken on the lines 3—3 of Figure 1.

Referring to the drawing wherein like numerals designate corresponding parts throughout the drawing, the numeral 10 designates the body portion of the holder, which in the present instance, is preferably constructed of flexible or resilient material, such as rubber or the like, which will not be materially affected by contact with water or other moisture.

The body 10 may be of any desired thickness and is preferably rectangular in cross section and is preferably provided with rounded or cutoff corners 11. The body 10 is provided with an elongated concave groove 12 which extends substantially the length of the body.

The upper edge portions of the concave opening 12 preferably converge toward the upper surface of the body 10, and a substan-

tially key-shaped opening is provided at 13, the outer edge portion of the opening being considerably reduced from the inner portion thereof, so as to provide a pair of clamping edges for holding the steel wool or the like, therebetween.

The outer edges of the groove 14 are preferably mounted on the body in spaced relation to each other, and a plurality of studs 15 may be mounted at their lower ends in the body 10, the upper ends thereof extending upwardly into the groove.

The studs are provided with an enlarged head portion 16 which is substantially elliptical in form, the opposite end portions being substantially pointed, as at 17, and downwardly inclined for securely holding the steel wool within the groove.

The studs 15 may be mounted on a substantially horizontal bar 18 which may be molded or otherwise secured in the body 10, or if desired the studs 15 may be mounted independent of each other, so as not to interfere with the flexing of the body portion, while in operation.

The studs 15 are preferably mounted in the body portion spaced inwardly from the outer ends of the groove and in spaced relation to each other. The heads 16 of the studs are substantially larger than the distance between the inwardly extending edges 14 of the groove, so that the edges 14 substantially overlie the pointed ends of the studs.

In use the body 10 may be flexed so as to enlarge the groove and to project the heads 16 of the studs outwardly of the groove. The body may then be pressed upon a pad of steel wool and permitted to assume its normal position, whereupon the gripping edges 14 will force the steel wool inwardly of the opening 13 so as to be engaged upon the pointed ends of the studs.

The pad of steel wool will then be securely mounted on the holder and can be used for scouring or cleaning. The heads of the studs 15 being positioned substantially below the outer surface of the body 10 will permit the use of the steel wool until it has been practically worn out, without scratching the heads of the studs.

In order to permit the convenient use of this device the body portion 10 may be provided with an elongated upstanding handle member 19. The opposite side portions of the body 10 may also be provided with outstanding flanges 20 which facilitate the flexing of the body 10 so as to permit of the ready insertion of the steel wool in the groove 14.

It is, of course, understood that various changes and modifications may be made in the details of construction and design of the above specifically described embodiment of the invention without departing from the spirit thereof, such changes and modifications being restricted only by the scope of the following claims.

What is claimed is:—

1. A holder adapted for holding a pad of steel wool or the like, comprising a flexible body portion, said body portion having a groove therein, and a plurality of elliptical headed stud members spacedly positioned in said groove for holding the steel wool on the body, said headed members lying normally below the surface of said body member and extending transversely of said groove.

2. A holder of the character described comprising a flexible body member having a groove therein, said groove being provided with a concave inner portion, and a plurality of studs mounted in said body and positioned within said groove, whereby to engage a pad of steel wool, said studs having elliptical headed portions positioned transversely of said groove.

3. A holder of the character described comprising a resilient elongated body member having a longitudinally arranged groove therein, and a plurality of holding members mounted in said groove, said holding members comprising a stud positioned in the body and extending outwardly into said groove, and an elliptical head portion for said stud, said head portion being positioned inwardly of the outer face of the body.

4. A holder of the character described, comprising a flexible body member, said body having a groove therethrough, the inner portion of said groove being concave, and a plurality of studs spacedly positioned within said groove, said studs having enlarged pointed head portions, said pointed head portions being inclined inwardly, whereby to engage the steel wool for holding the wool within the groove.

5. A holder of the character described comprising a flexible body member having a groove therein, the opposite side portions of said groove being inclined to provide undercut inner side portions of said groove, and a plurality of steel wool engaging members mounted on said body in said groove.

In testimony whereof I hereunto affix my signature.

SAUL SCHULHOFF.
